2 SHEETS--SHEET 2.

UNITED STATES PATENT OFFICE.

DAVID JOSEPH DORSEY, OF BATON ROUGE, LOUISIANA.

SHADE AND CURTAIN HANGER.

1,328,136.

Specification of Letters Patent. Patented Jan. 13, 1920.

Application filed June 17, 1919. Serial No. 304,768.

To all whom it may concern:

Be it known that I, DAVID J. DORSEY, a citizen of the United States, residing at Baton Rouge, in the county of East Baton Rouge, State of Louisiana, have invented 5 certain new and useful Improvements in Shade and Curtain Hangers; and I do hereby declare the following to be a full, clear, and exact description of the invention, such 10 as will enable others skilled in the art to which it appertains to make and use the same.

This invention relates to new and useful improvements in shade and curtain hangers.

15 One object of the present invention is to provide a novel and improved device of this character by means of which the shade and curtain can be easily and quickly hung in position or removed from the window frame 20 without the use of a ladder, chair, or other elevated device.

25 Another object of the invention is to provide a novel and improved structure of the said character by means of which the shade can be moved bodily to any height with respect to the window frame.

30 Other objects and advantages will be apparent from the following description when taken in connection with the accompanying drawing.

In the drawing:

Figure 1 is an elevation of the device in proper position on the window frame.

35 Fig. 2 is a vertical sectional view taken on the line 2—2 of Fig. 1.

Fig. 3 is a top plan view of the device.

Fig. 4 is a horizontal transverse sectional view taken on the line 4—4 of Fig. 1.

40 Fig. 5 is an enlarged vertical sectional view taken on the line 5—5 of Fig. 1, the intermediate portion being broken away.

Fig. 6 is an enlarged horizontal sectional view taken on the line 6—6 of Fig. 1, showing the lower brackets for the vertical side 45 bars 13.

Fig. 7 is a front elevation, similar to Fig. 1, but showing a modification in the arrangement and construction of the operating levers and pawls.

50 Fig. 8 is a horizontal sectional view taken on the line 8—8 of Fig. 7, showing the arrangement of the lever and pawl, with respect to the bar 13.

Referring to the accompanying drawings, 55 and especially to Figs. 1 to 6, 10 represents the vertical side stiles and 11 the upper

transverse member or heading of the window frame, in connection with which my invention is used.

Secured to each end of the front face of 60 the heading 11 is a socket member 12. Disposed vertically in spaced relation outwardly from the front faces of the side stiles 10 are the bars 13, each having a series of ratchet notches 14 along its outer 65 edge. The upper end of each of the bars is bent to form a hook 15 which is engaged in one of the socket members 12. Secured to the lower portion of each of the stiles 10 is a bracket 16 which has an outwardly ex- 70 tending bifurcated portion 17 for the reception of the lower reduced and threaded end of one of the bars 13, a winged nut 18 being engaged on the said end, below the bifurcation, for holding the rod therein and at the 75 same time drawing the rod or bar downwardly to insure the retention of the hook 15 in the socket 12. Thus the bars are held against vertical or lateral movement and in firm and rigid position with respect to the 80 window frame, and in parallel relation to each other.

Disposed transversely of the upper portions of the bars 13 is a member 19 the end of which extend short distances beyond the 85 sides of the bars, and rotatably mounted on this member and engaging with the opposite vertical edges of the bars, are the rollers 20, a plate 21 being secured to each end of the member, outwardly of the bar 13 to retain 90 the rollers in engagement with the bars. Pivotedly connected to each end of the member 19 is a downwardly extending lever 22, each carrying a projection 23 engaged with the adjacent edge face of a bar 13 and arranged to engage in the notches thereof. Coil springs 24, connected at their ends to the member 19 and to the levers 22, hold the levers normally in a position such that the projections thereof will be pressed firmly 95 against the edge faces of the bars. By pushing upwardly or pulling downwardly on the levers 22, the levers will be released from the notches and the member 19 raised or lowered, upon 100 pushing upwardly or pulling downwardly on the levers 22.

Secured to and depending from each end of the member 19, inwardly of the bars 13, is a bracket 24', said brackets being formed, 110 on their lower ends for the reception of the pintles of the ends of the shade roller 25.

Extending outwardly from the upper end of each of the bars 13 is a curtain pole supporting bracket 26, for the curtain pole 27.

As clearly seen in Fig. 1, the lower ends 5 of the bars 13 are secured at points on the window frame approximately midway of the height thereof, and secured to and extending outwardly from the said ends of the bars, immediately above the brackets 16, for 10 the support of a half curtain pole or cord are the eyes 16'.

It will thus be seen that by engaging the hooked ends of the bars 13 in the socket members at the top of the window frame, 15 and then securing the lower ends of the bars in the bifurcations of the lower brackets, the said bars can be placed in position on the window frame without the necessity of a chair, ladder or means to secure the elevation 20 of the person. To remove the entire fixture, it is only necessary to loosen the winged nuts, and then lift the bars, with all of the attached parts, from the window frame.

25 When it is desired to lower the shade, to permit entrance of air over the upper open sash of the window, the levers are swung on their pivots to disengage their projections from the notches of the bars, and the member 19, with the shade thereon, lowered to the desired position. When the desired position is reached, the levers are permitted to swing outwardly, under the influence of the springs 24, when the projections of the 30 levers will engage in corresponding notches of the bars 13 and hold the parts in such position until it is desired to raise the shade again.

In Figs. 7 and 8 there is shown a modification 40 of the lever and pawl which engages with the bar. In this form the upper ends of the bars 13' carry bolts 28 which engage in longitudinal slots 29 in the ends of a bar 30 disposed above the bar 19'. A member 45 31 has one end bifurcated and disposed in straddling relation to the bar 13' and the end of the member 19', the legs of said bifurcation being pivoted to the said member 19'. Disposed vertically between each end of the 50 member 19' and its end plate 21', is the upper end of the modified form of lifting

lever, shown at 32. The upper end of the lever, above the members 19' and 21', carries a nut, while below the said members the lever has a bearing plate 33, against which 55 the upper end of a coil spring 34 bears. This spring is disposed in encircling engagement with the lever and bears with its lower end against the outer horizontal portion of the member 31, and through which 60 the lever is slidably disposed. It will be noted that the bight portion 35 of each of the members 31 bears frictionally against the edges of the vertical members 13', and that the springs 34 exert a canting action on 65 the said members so that said bight portions will be forced into one or another of the notches when the members are slipped along the members 13'. By an outward rocking movement of the lever the member 31 will 70 be disengaged from the notch of the member 13', to permit the member 19' to be moved vertically on the members 13', to the height desired. Upon release of the lever it will be moved by the spring to reengage its bight 75 portion with a notch.

What is claimed is:

A shade and curtain hanger including vertical parallel bars having notches in their outer vertical edges, socket members carried 80 by the upper portion of the window frame, the upper ends of said bars being formed for engagement in said socket members, bifurcated brackets on the lower portion of the window frame, the lower ends of the bars 85 being threaded and removably engageable in said bifurcations, clamping nuts on said threaded ends for engagement with said bifurcations, a transverse member disposed between said bars, bar engaging rollers on 90 the said transverse member, shade supporting means on the member, and movable spring urged levers carried by the transverse member and having means for engagement within the notches to hold the said 95 member at different elevations on said bars.

In testimony whereof, I affix my signature, in the presence of two witnesses.

DAVID JOSEPH DORSEY.
